DESIGN FOR A COMBINED COVER AND
UTENSIL SUPPORTING STRUCTURE FOR
COOK STOVE TOP BURNERSClaude E. Parker, Chicago, Ill., assignor to Gas
Products Corporation, Chicago, Ill., a corpora-
tion of Illinois

Application August 3, 1940, Serial No. 94,205

Term of patent 7 years

To all whom it may concern:

Be it known that I, Claude E. Parker, a citizen of the United States, residing at Chicago, in the county of Cook and State of Illinois, have invented a new, original, and ornamental Design for a Combined Cover and Utensil Supporting Structure for Cook Stove Top Burners, of which the following is a specification, reference being had to the accompanying drawing, forming part thereof.

Figure 1 is a plan view of a combined cover and utensil supporting structure for cook stove top burners showing my new design.

Fig. 2 is a perspective view of said structure.

The design is characterized particularly by the provision of three equidistant radial arms in the generally disk shaped structure with segments intervening between the arms and coacting therewith to form three slots, substantially as shown.

I claim:

The ornamental design for a combined cover and utensil supporting structure for cook stove top burners, substantially as shown and described.

CLAUDE E. PARKER.
